FOOTBALL WITH SPIRAL SEAMS

Frank G. Kroener, 1755 E. Ocean Blvd.,
Newport Beach, Calif. 92661

Filed June 4, 1973, Ser. No. 366,601

Term of patent 14 years

Int. Cl. D21—01

U.S. Cl. D34—15 EE

Fig. 1

Fig. 2

FIG. 1 is a side elevation view of a football showing my new design; and

FIG. 2 is a front elevational view of the football showing my new design.

The spiral seams of my design may run in a counter-clockwise direction, as shown in FIG. 2, or in a clockwise direction.

I claim:

The ornamental design for a football with spiral seams, substantially as shown and described.
